PROCESS OF ALKYLATION WITH
CHLOROSULPHONIC ACID

William E. Bradley, Los Angeles, Calif., assignor
to Union Oil Company of California, Los
Angeles, Calif., a corporation of California

No Drawing. Application May 31, 1938,
Serial No. 211,045

8 Claims. (Cl. 196—10)

The present invention relates to the treatment of hydrocarbons, and more particularly pertains to the synthesis of paraffinic hydrocarbons of a branched chain type especially suitable for use as automobile and aviation engine fuels or as constituents thereof.

In a more specific sense, the invention comprises or includes a process for the combining of isoparaffinic hydrocarbons of relatively low molecular weight with olefinic hydrocarbons, which may be normally gaseous or normally liquid, or both, to produce branched chain paraffinic hydrocarbons boiling within the gasoline range and possessing high antidentalating characteristics. The invention further resides in the discovery of a new catalyst particularly suitable for effecting the chemical combination of the low molecular weight isoparaffins with olefinic hydrocarbons to produce motor fuels having the desired knock-rating characteristics.

Oil cracking processes which are at present in use as a means of supplementing the supply of gasoline obtainable by the straight run distillation of crude oils, and also for producing materials which have higher knock-rating values than these straight run gasolines, result in the formation of considerable quantities of by-products. The gaseous fractions produced during these cracking operations contain relatively large percentages of olefinic hydrocarbons, particularly of the normally gaseous type. It is one of the main objects of the present invention to provide a process for a more efficient utilization of these and other olefins or olefin-containing gases. Aside from the olefinic hydrocarbons produced during the above outlined petroleum cracking operations, olefins also occur or result from gas-making processes and may be produced as by-products in various chemical industries as well as by the simple dehydrogenation of paraffinic hydrocarbons. In general, olefinic hydrocarbons exhibit a high reactivity in their tendency to polymerize and to form substances of higher molecular weight. On the other hand, paraffinic hydrocarbons, such as isobutane and isopentane, which normally occur in natural gas or similarly related materials, are usually considered to be more or less chemically stable and are incapable of polymerizing.

It is a further object of the present invention to provide for a more efficient utilization of certain of the isoparaffinic hydrocarbons and the aforementioned and other olefinic hydrocarbons to produce highly valuable derivatives therefrom. A still further object of the present in-

vention resides in providing for an efficient utilization of the low boiling isoparaffinic hydrocarbons, namely, isobutane, isopentane and isohexane, and of the normally gaseous olefinic hydrocarbons including propylene, the butylenes and the pentenes, and of the relatively low boiling normally liquid hydrocarbons, to produce branched chain paraffinic hydrocarbons of high anti-detonating characteristics and boiling substantially within the gasoline range.

The reaction between one or more olefinic molecules and one or more isoparaffinic molecules produces one or more branched chain paraffinic molecules. This reaction is termed "alkylation" and the product is herein called an "alkymer" in order to distinguish it from a "polymer" which is the product resulting from the interaction of two or more olefinic molecules. Theoretically, the reaction between an isoparaffin and an olefin in the presence of a suitable alkylating catalyst, is of a simple character. Thus, when an isobutane molecule is chemically combined with a butylene molecule, the resultant product is an octane. Thus:

Similar reactions may be written for the alkylation of isobutane or other isoparaffins with various olefins.

The above alkylation reaction exemplifies the simple chemical combination of isoparaffinic molecules with olefinic molecules introduced into the reaction sphere. However, as will be brought out hereinbelow, the term "alkylation" as employed in this specification includes not only the simple chemical addition of an olefin to an isoparaffin, but also includes the union between certain specified isoparaffinic molecules and olefinic molecules formed in situ, as by the depolymerization of relatively larger olefinic molecules.

As stated above, olefins, when subjected to proper reaction temperatures and pressures in the presence of suitable catalysts, such as sulphuric acid, etc., tend to polymerize and form unsaturated molecules of higher molecular weight. Under certain conditions of operation polymerization will occur in preference to alkylation and the reaction products will be found to contain only small percentages of alkymers, the greater proportion of the olefins having polymerized in preference to their addition to isoparaffinic hydrocarbons.

It is, therefore, another object of the present invention to provide a process wherein the al-

ylation of the isoparaffins by olefins will be favored in preference to the polymerization of the olefins introduced into the reaction zone. It is a further object of the invention to provide a process and a catalyst which will effect the combination of the olefins with the isoparaffinic hydrocarbons to produce branched chain paraffinic hydrocarbons having high anti-detonating characteristics and boiling substantially within the gasoline range, the products of reaction being essentially free from products of polymerization.

It is a still further object of the present invention to provide a process wherein the low boiling isoparaffinic hydrocarbons may be combined with normally gaseous and normally liquid olefinic hydrocarbons to produce valuable motor fuel fractions having high anti-detonating characteristics.

It has now been discovered that the above and other objects can be realized by conducting the alkylation reaction in the presence of chlorosulphonic acid. It has been further discovered that excellent yields of alkymers boiling within the gasoline range and having the desired anti-detonating characteristics may be produced by reacting the low boiling isoparaffinic hydrocarbons such as isobutane, isopentane and isohexane, with normally gaseous olefinic hydrocarbons, or with normally liquid olefinic hydrocarbons having preferably not more than 12 carbon atoms per molecule, or with both types of olefins, in the presence of chlorosulphonic acid, said alkylation reaction being preferably realized at temperatures substantially below room temperature.

It has been still further discovered that the above described alkylation reaction may be realized substantially in the liquid phase.

The invention may therefore be broadly stated to reside in reacting isoparaffinic hydrocarbons of the type of isobutane, isopentane, and isohexane, with normally gaseous or normally liquid olefinic hydrocarbons, or with both types of olefins, in the presence of a catalyst comprising chlorosulphonic acid, whereby the olefins are caused to chemically combine with the isoparaffins to form alkymers having high anti-detonating characteristics and boiling substantially within the gasoline range, the resultant material being substantially free from products of polymerization. The invention further resides in realizing the above alkylation reaction at sub-atmospheric temperatures, the reaction being conducted in the liquid phase.

The invention still further resides in conducting the above described alkylation reaction under conditions wherein the reacting products are maintained in a state of vigorous agitation. In order to minimize and even prevent the formation of polymerization products, the proportion of isoparaffins should be constantly in excess of that theoretically necessary to combine with the olefins introduced into the reaction zone. For this purpose it has been found advantageous to first commingle the isoparaffins with the catalyst, and then slowly and gradually introduce the olefins into the isoparaffin-catalyst mixture. The presence of this excess of isoparaffins and the gradual addition of the olefins prevents a local concentration of the olefins in the reaction mixture, such local high concentration of olefins being undesirable because of the increased tendency to polymerize instead of alkylate. The constant vigorous agitation of the mixture during the addition of the olefins likewise aids in preventing the occurrence of local concentrations of olefins.

In other words, both the agitation and the presence of isoparaffinic molecules in excess, and preferably a large excess of that theoretically necessary to combine with the olefins introduced, increases the chances of an immediate or substantially immediate, contact of the olefin with a reactive isoparaffinic molecule. Simultaneously, and in accordance with the "Law of mass action," the relatively slow addition of the olefins decreases their concentration in the reaction zone, thus also increasing the possibility of the alkylation reaction taking place in preference to polymerization.

The term "isoparaffin" when used herein, relates to the lower members of this series, and includes isobutane, isopentane and isohexane. The rates of reaction of these low molecular weight isoparaffins, maintaining other conditions equal, are not the same. Thus, it has been discovered that the rate of alkylation when isopentane is employed is considerably slower than that of isobutane, while isohexane is alkylated even at a slower rate than isopentane.

As previously brought out the term "olefins" relates to both the normally gaseous olefins, such as propylene, the butylenes and the pentenes, and the normally liquid olefins. In most instances, it is preferable although not essential, to employ olefinic fractions which do not have more than twelve carbon atoms per molecule.

It is further understood that the reference to isoparaffinic and olefinic hydrocarbons includes the use of these hydrocarbons individually, or in admixture with other hydrocarbons of the same class, or with other hydrocarbons.

The following example serves to show how the catalytic addition of olefinic hydrocarbons to isoparaffinic hydrocarbons may be effected in the presence of chlorosulphonic acid. It is to be understood, however, that the method of application of this new catalytic substance is not limited to the described mode of operation.

In this experiment the isoparaffinic fraction employed comprised a relatively narrow cut obtained from the stabilization of natural gasoline. An analysis of this fraction indicated that it consisted of about 20.2% by volume of propane and 79.3% by volume of isobutane, the residue being normal butane. It is obvious however, that the isoparaffinic fraction to be alkylated according to the present invention may consist of other isoparaffinic hydrocarbons. Thus, as stated, it is possible to alkylate isopentane or isoparaffinic fractions comprising a mixture containing isopentane or isobutane and other isoparaffins.

The specific olefin-containing fraction was derived from petroleum cracking operations and had substantially the following composition:

	Percent by volume	Percent
Ethylene	0.2	
Ethane	1.5	
Propylene	13.4	
Propane	28.3	
Isobutylene	18.1	
n-butylene	11.1	
Isobutane	18.3	
n-butane	9.1	

In the particular experiment, the reaction was continued for about eight hours at a temperature of between -21° and -29° F., this low temperature being realized by keeping the reaction vessel in a bath containing kerosene and dry-ice. Since these low temperatures were suf-

ficient to maintain the hydrocarbons substantially in the liquid state, the reaction was realized at atmospheric pressure.

The procedure employed was as follows: 1750 grams of the above described isobutane-containing fraction was first commingled with about 1750 grams of chlorosulphonic acid, and approximately 3185 milliliters of the olefin-containing fraction was then gradually conveyed to the reaction zone, the rate of introduction being about 6.6 milliliters per minute. Since the analysis of this olefin-containing fraction showed that it contained about 42.6% of unsaturates, the olefin introduction was at the rate of about 2.82 milliliters per minute. During the reaction period the mixture was maintained in a state of vigorous agitation by a centrifugal type stirrer moving at the rate of 650 R. P. M. Approximately thirty minutes after all of the olefinic stock had been added to the reaction chamber, agitation was discontinued and the reactor was maintained at a temperature of -30° F. for several hours in order to allow phase separation to take place. The acid and hydrocarbon phases were then separately removed from the reactor, and the hydrocarbon phase analyzed to determine the quantity and character of the alkymers produced.

It was thus found that 1575 grams or 2225 milliliters of stabilized alkymers had been produced, this being equivalent to a yield of 164.2%, by volume based on the olefin employed. The stabilized alkymers fraction was completely saturated, thus indicating that substantially no polymerization products had been formed during the reaction. The gravity of this alkymers was 68.7° A. P. I. The knock-rating of this fraction, as determined by the A. S. T. M. method, was 88.0. The Engler distillation range of the product was as follows: Initial boiling point -115° F., 10% overhead at 160° F., 50% overhead at 222° F., 90% overhead at 347° F., and maximum boiling point 418° F. This distillation resulted in a 98.0% recovery without any cracking.

Approximately 78% by volume of this alkymer distilled over at 325° F., the resulting distillate, equivalent to 128.1% by volume of the olefins originally added into the reaction zone, having a knock-rating of 90.0 and a gravity of 70.3° A. P. I. The Engler distillation curve of this distillate indicated that it was suitable as an aviation motor fuel. Thus, its initial boiling point was 126° F., 10% overhead at 176° F., 50% overhead at 202° F., 90% at 256° F., with a maximum distillation temperature of 332° F., and 99.0% of the fraction was recovered as overhead.

As pointed out above, the alkylation of isoparaffins with olefins in the presence of chlorosulphonic acid as a catalyst should preferably be realized at substantially low temperatures. To show the advantage of operating at these low temperatures another run was conducted at a temperature of approximately 0° F. In this case, the reaction product comprised 107% by volume of the olefins employed, this reaction product containing 8% of products of polymerization. The knock-rating of the product was 87.

A comparison of the above data with that given hereinabove in connection with the run conducted at lower temperatures, indicates the advantages of operating at such lower temperatures. Thus, whereas at least some polymerization occurred during the reaction at 0° F., the products of alkylation were completely saturated

when the run was carried out at the -21° to -29° F. temperature. Also the volume of the desirable products of reaction were about 50% greater when the reaction was realized at -21° to -29° F. than when carried out at 0° F.

It is to be understood that there is no intention to be limited to the specific low temperatures disclosed hereinabove, the examples being merely indicative of the advantages obtained by employing sub-atmospheric temperatures. Thus, it is within the scope of this invention to employ temperatures as low as -50° F., and even lower. However, in order to maintain the reaction in the liquid phase, the temperature should be above the point of solidification of chlorosulphonic acid. Also, although the above described experiments were realized at atmospheric pressures, it is to be understood that higher or lower pressures may be employed especially for the purpose of maintaining the reacting products in a liquid state at the operating temperature.

The alkylation reaction in the presence of chlorosulphonic acid and under the conditions described above, should be preferably realized in the absence of any water in the reaction zone. For this purpose, the reacting hydrocarbons may preferably be dehydrated before their introduction into the sphere of reaction. This may be realized, for example, by conducting the isoparaffins and the olefins through or over dehydrating agents, such as a bed of NaCl, CaCl₂, Na₂CO₃, or a similar material. Any other method or means of removing water which will not alter the character of the reacting hydrocarbons can be employed, and is deemed to be within the scope of the invention.

The above disclosure is presented primarily in connection with the alkylation of isoparaffins with olefins, emphasis being placed on the simple addition of the relatively low molecular weight, normally gaseous olefins to the specified isoparaffins. In addition, however, it has been observed that in reacting the described isoparaffins with normally liquid olefinic hydrocarbons, the reaction product comprised a large proportion of saturated hydrocarbons of branched chain structure boiling substantially within the gasoline boiling range. Such hydrocarbons evidently could be formed by an initial scission of at least one of the reacting original hydrocarbons into two or more hydrocarbons of lower molecular weight and the subsequent reaction of these lower molecular weight hydrocarbons to produce branched chain paraffinic hydrocarbon molecules. Alternatively, the above product may be the result of a simple addition of the introduced olefinic molecule to an isoparaffinic molecule in the reaction zone, followed by a scission of the resulting product. This type of alkylation might be termed "cracking alkylation" in order to distinguish it from the straight or simple addition of an olefin to an isoparaffin as already described hereinabove. Therefore, the "cracking alkylation" reaction may be described as including the step of reacting olefin molecules with isoparaffin molecules to produce one or more paraffinic molecules having molecular weights less than that which would be obtained if the reaction were of the simple addition type in which one introduced olefinic molecule reacted with one isoparaffinic molecule to produce an isoparaffinic alkymers having a molecular weight equal to the sum of the molecular weights of the reacting olefin and isoparaffin.

Therefore, the invention also includes the re-

action between isoparaffins and certain of the olefins, in the presence of chlorosulphonic acid as a catalyst and under optimum temperature and pressure conditions, to produce simple alkylation of the isoparaffins by the olefins added, and the cracking alkylation in which, as stated, alkymers are produced which have a lower molecular weight than would be obtained by a simple addition of an olefin to an isoparaffin. Primarily, this cracking alkylation occurs when the isoparaffins of the class described are caused to react, in the presence of chlorosulphonic acid, and at the described low temperatures, with the normally liquid olefinic hydrocarbons. The higher molecular weight olefins, and particularly those above dodecenes, however, appear to be unsuitable to react with isoparaffins.

The chlorosulphonic acid used therein as the alkylating catalyst is an acid having the general formula SO_2OHCl . Its molecular weight is 116.531. It is a substantially colorless, fuming liquid having a rather piquant odor. The melting point of this acid is approximately -80° C . while its boiling point is variously given as being between about 145° and 158° C . This acid may be prepared, for example, by the direct addition of hydrogen chloride to sulphur trioxide. However, there are other methods for preparing this acid catalyst. For other characteristics of chlorosulphonic acid, as well as for the various methods of its manufacture, reference is made to such authorities as J. W. Mellor's treatise entitled "A Comprehensive Treatise on Inorganic and Theoretical Chemistry," 1930, vol. X, pages 686-687.

The term "gasoline boiling range," as employed herein, refers to the average boiling range of fuels used in ordinary automobile engines. Generally speaking, such a gasoline has an initial boiling point of about 100° F , and a maximum or end point of around 425° F . The term "atmospheric pressure" refers to pressures in the neighborhood of that exerted by a column of mercury 760 mm. in height, while "atmospheric temperature" relates to temperatures in the neighborhood of 70° F . to 80° F .

In carrying out the invention, the apparatus used, as well as the conditions of operation chosen, will be varied to suit the individual case.

The foregoing specification is to be considered as merely descriptive of the process and catalyst, and is not to be considered as imposing any undue limitations upon its generally broad scope as covered by the appended claims.

I claim:

1. A process for the production of branched chain hydrocarbons boiling within the gasoline boiling point range and having high anti-detonating characteristics, which comprises reacting isoparaffins having less than seven carbon atoms per molecule with normally gaseous olefins in the presence of chlorosulphonic acid between the temperatures of 0° F . and the solidification temperature of chlorosulphonic acid.

2. A process for the production of branched

chain paraffinic hydrocarbons, which comprises commingling isoparaffinic hydrocarbons having less than seven carbon atoms per molecule with a catalyst comprising chlorosulphonic acid between the temperatures of 0° F . and -50° F ., introducing normally gaseous olefins into said acid-isoparaffin mixture, and withdrawing alkylated branched chain hydrocarbons from the reaction zone, said last mentioned hydrocarbons being liquid under normal conditions of pressure and temperature.

3. In a process according to claim 2 wherein the acid-isoparaffin mixture is maintained in a state of agitation, and wherein the olefins are introduced gradually into said violently agitated mixture.

4. A process of forming alkylated branched chain hydrocarbons having high anti-detonating characteristics, and suitable as motor fuel, which comprises reacting isoparaffinic hydrocarbons having less than seven carbon atoms per molecule with normally liquid olefins having less than thirteen carbon atoms per molecule, in the presence of a catalyst containing chlorosulphonic acid.

5. In a process according to claim 4 wherein the reaction is realized at sub-atmospheric temperatures.

6. A process of forming alkylated branched chain hydrocarbons boiling substantially within the gasoline range, having high anti-detonating characteristics, and substantially free from polymers boiling within said range, which comprises commingling isoparaffinic hydrocarbons having less than seven carbon atoms per molecule with a catalyst comprising chlorosulphonic acid, maintaining said mixture in a state of agitation and at sub-atmospheric temperatures, and introducing into said isoparaffin-catalyst mixture normally liquid olefinic hydrocarbons below about dodecenes, thereby causing a reaction between said olefins and isoparaffins to produce said branched chain saturated hydrocarbons.

7. In a process according to claim 6 wherein the reaction is realized at temperatures between about 0° F . and the solidification temperature of chlorosulphonic acid.

8. A process of forming alkylated branched chain hydrocarbons boiling substantially within the gasoline range, having high anti-detonating characteristics and substantially free from polymers within said range which comprises commingling iso-butane with chlorosulphonic acid, maintaining said mixture in a state of agitation and at temperatures of between about -20° F . and -50° F ., introducing into said isobutane-catalyst mixture normally gaseous olefinic hydrocarbons, thereby causing a reaction between said olefins and said isobutane to produce said alkylated hydrocarbons, and separately withdrawing said branched chain alkylated hydrocarbons.

WILLIAM E. BRADLEY.
